UNITED STATES PATENT OFFICE.

CHARLES H. ALLAN, OF RYEGATE, MONTANA.

ROLLER CHUTE SPRING FOR TYPESETTING MACHINES.

Application filed April 6, 1928. Serial No. 268,000.

This present invention lies in providing a chute spring with a rotatable element or roller at its lower end adapted to contact with a minimum of friction with a matrix passing thereunder. Since the matrix in passing away from the roller causes the latter to spin, I provide as a further feature a braking device for the rotatable element, the braking device being normally operative but being released while a matrix is in contact with the rotatable element.

The purpose of the present invention, is to eliminate the possibility of clogging in the chute. With the devices of the prior art such clogging not infrequently occurs, due to the fact that when the matrix strikes the assembler matrix rod it is still in contact with the chute spring, and if the matrix is dirty or gummy, or the star wheel worn, the frictional engagement of the matrix by the chute spring is not overcome. I have found that by providing the chute spring with a roller at this clogging point stoppages are absolutely avoided, due to the minimum resistance offered to the matrix by the roller.

An embodiment of my invention is shown in the accompanying drawings, wherein

Figure 1 is a side elevation of my improved chute spring and the associated parts of a typesetting machine.

Figure 2 is a top plan view of the chute spring.

Figure 3 is a section on the line 3—3 of Figure 2, and

Figure 4 is a section on the line 4—4 of Figure 2.

Referring now to the drawings, it will be seen that the chute spring, which is designated as a whole by the numeral 10 is secured at its upper end in the usual manner to a fixed part 11 of the machine so that its foot extends in proximity with slide 11', which receives the matrices from the belt 12. Referring to Figures 2 and 3 in particular, the chute spring 10 comprises a main upper portion 13 and a separable lower end portion 14. The end portion 14 is secured to the main portion 13 by means of lateral tongues 15 and 16 and a central tongue 17 passed up through an aperture in the main portion. End portion 14 is bifurcated to form vertical walls 18 and 19, between which is supported a roller 20 by means of a spindle 21 journalled in the bifurcations. The main portion of element 14 underlies element

13 as is clearly shown in Figure 3, and in order to give the chute spring a smooth lower end surface a thickening piece 22 is secured to element 13 by means of a rivet 23 and rivets 23'. The rivet 23 also secures in position a spring arm 24, which projects over and beyond roller 20, the free end 24' of the spring arm being bent downwardly so as to be engaged by the matrix 25, Figure 1, while the latter is in contact with roller 20.

Spring arm 24 is normally in contact with roller 20, but as the matrix passes under the latter its upper surface engages and lifts end 24', so that the arm is released from the roller and the latter may thus rotate freely. The spring arm is made of very light material, and offers no appreciable resistance to the passage of the matrix. End 24' falls into the bifurcation of the matrix as the latter passes out of contact with the roller.

Roller 20 may be formed of any suitable material, but I prefer to make it of hard fiber. Excessive wear of the spindle 21, and its bearings is prevented by the braking device 24, but if these parts become worn from long use they may be removed by simply detaching foot portion 14.

It will be understood that modifications as to detail will be possible without departing from the spirit of my invention, as set forth in the following claims.

I claim:

1. The combination with a chute spring for typesetting machines, of rotatable means carried by said spring in position to contact with the upper face of a matrix passing thereunder.

2. The combination with a chute spring for typesetting machines, of a roller carried by said spring in position to contact with the upper face of a matrix passing thereunder.

3. The combination with a chute spring for typesetting machines, the lower end of said spring being bifurcated, of a roller journalled between said bifurcations in position to contact with the upper face of a matrix passing thereunder.

4. The combination with a chute spring for type setting machines, said spring including a detachable bifurcated lower end section, of a roller journalled between the bifurcations of said end section in position to contact with the upper face of a matrix passing thereunder.

5. The combination with a chute spring for

typesetting machines, of rotatable means carried by said spring in position to contact with the upper face of a matrix passing thereunder, and brake means for said rotatable means.

6. The combination with a chute spring for typesetting machines, of rotatable means carried by said spring in position to contact with the upper face of a matrix passing thereunder, and brake means for said rotatable means released by the matrix while the latter is in contact with said rotatable means.

7. The combination with a chute spring for typesetting machines, of rotatable means carried by said spring in position to contact with the upper face of a matrix passing thereunder, yieldable means normally bearing against said rotatable means to restrain the

rotation thereof, and means engaged by the matrix while the latter is in contact with said rotatable means for releasing said yieldable means.

8. The combination with a chute spring for typesetting machines, of a roller carried by said spring in position to contact with the upper face of a matrix passing thereunder, and a spring arm secured at one end to the chute spring and extending over said roller in contact therewith, the free end of said spring arm being engaged by the matrix while the latter is in contact with said roller to raise the arm from the roller.

In testimony whereof I have hereunto set my hand.

CHARLES H. ALLAN.
